UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

MAGNETO.

Application filed April 19, 1921; Serial No. 462,583.

To all whom it may concern:

Be it known that I, EDWARD B. NOWOSIELSKI, a citizen of the United States, residing at Bloomfield, in the county of Essex, State 5 of New Jersey, have invented certain new and useful Improvements in Magnetos, of which the following is a description, reference being had to the accompanying drawing and to the figures of reference marked 10 thereon.

This invention relates to magnetos wherein in a rotor bearing a plurality of inductors of permeable material transmits magnetic flux from pole pieces of constant polarity 15 thru an induction coil to generate a current in the coil.

Electric machines of the above character are employed with internal combustion engines to furnish the spark to ignite a charge 20 within the explosive chamber of the engine. In order that the maximum effect of the generated current be produced in the form of a spark, it is desirable that the primary circuit of the coil be broken at the instant that the 25 peak of the electro-motive force wave is created and this peak must correspond in time with that position of the piston in the engine which is most effective and desirable. The peak of the wave in magnetos of the above 30 character takes place almost immediately after the inductors break the magnetic circuit thru the magnet poles, inductors, and core of the induction coil. When the spark and consequently the break is required at regular intervals no great difficulty is found 35 in designing a magneto to break the magnetic circuit at regular intervals and at the time when a spark should occur in the cylinders of the engine. But when the cylinders are inclined to each other, and a shifting 40 of the electro-motive force waves is necessary to effect alternately longer and shorter intervals between peaks, the problem is not so easy.

It is an object of this invention to construct a magneto to fire at irregular intervals with a symmetrical magnetic field.

It is a further object of this invention to construct a magneto adapted to fire at irregular intervals using, in one form of my invention, stock rotor elements all of the same size and shape and stock pole pieces, also of the same size and shape, the same rotor elements and pole pieces being used 55 for all magnetos irrespective of the firing

intervals of the magneto, it being only necessary to incline the inductor elements of the rotor to each other at an angle characteristic of the intervals of firing desired.

Other and further objects will appear after 60 reading the following specification and claims in connection with the accompanying drawings in which—

Figure 1 is a view of the base of my magneto, the permanent magnets and the induction coil and core being shown only fragmentarily in dotted lines. 65

Figure 2 is a perspective view of the rotor of my magneto showing the two pairs of inductors borne thereby. 70

Figure 3 is a cross sectional view of the base of the magneto.

Figure 4 is a cross sectional view thru the front and back of the rotor along the lines 75 4—4, 4—4.

Figure 5 is a cross sectional view of the elements of the rotor of a modified form of my invention, a portion of one of the inductors being cut away.

Figure 6 is a cross sectional view of the 80 elements of the rotor of another modified form of my invention, in this instance both magnetic elements of a pair being modified.

Figure 7 is a further modification of the front pair of inductors of Figure 6. 85

Figure 8 shows still another modification in which merely a groove is cut in one of the inductors of a pair, for a purpose which will hereinafter be disclosed.

Figure 9 shows a still further modification 90 in which the end of one of the inductors of a pair is cut away.

Figure 10 shows diagrammatically the relative positions of the inductors of the rotor, the pole pieces of the induction coil 95 and the magnet pole pieces as well as the circuit breaker at the instant of breaking of the magnetic flux path.

Figure 11 shows the position of the various parts of another point of break of the 100 flux path.

Figure 12 is an oscillogram showing the performance of a magneto furnished with the rotor element illustrated in Figure 4.

Figure 13 is a similar oscillogram with 105 the rotor illustrated in Figure 7, the curve in all respects, however, being the same as would be furnished by the rotor illustrated in Figures 6, 10 and 11.

In the several figures, 1 indicates a base 110

of non-magnetic material such as aluminum, in which is embedded a pair of magnet pole pieces 2 and 3, on which are adapted to rest the feet of a permanent horseshoe magnet 4, 5 the two pole pieces 2 and 3 being of opposite but constant magnetic polarity. Also embedded in the base is a pair of spaced aligned soft iron coil pole pieces 5 and 6, as shown in Figure 1, bridged by an induction 10 coil having a core 7, said core having a coil 8 wound thereabout. Rotating in the base is a rotor having two pairs of inductors 9, 10, 11, and 12, embedded in a non-magnetic material 13, such as aluminum, cast about 15 the rotor shaft 14. In the form of invention illustrated in Figure 4, all of the inductors are of exactly the same size and shape and may be punched out with the same die. These inductors are inclined to 20 one another at such an angle as to correspond with the firing intervals desired, that is to say, at one half the angle between the V arrangement of the cylinders, it being understood that the magneto runs at half engine crank shaft speed, and it can be readily 25 understood that by merely casting the inductors on the rotor with the elements of a pair at an angle to each other proportional to the angle of inclination of the cylinders 30 that any irregular firing intervals may be obtained.

In the form of invention as illustrated in Figure 4, the forward pair of inductors are of exactly the same conformation as the 35 rear pair and the elements of the two pairs of inductors are inclined toward each other at the same angle, the axis of symmetry thru the two pairs, however, being displaced 90 degrees. In the form illustrated in Figure 4, one of the inductors of the forward pair is cut away as at 15 for a purpose which will be apparent hereinafter. In Figures 8 and 9 a groove 16 and a notch 17, respectively, is cut adjacent the edge of one of the inductors for the same purpose as the cut away portion 15. In Figure 6 I have shown a still further form of my invention. In this case a portion 18, as indicated by the dotted line, is added to one of the inductors diagonally opposite to the cutaway portion 15 of the same pair. In Figure 7 I have so cut the inductor 10 as to make it symmetrical with respect to the horizontal axis, the inductor, however, functioning exactly as the inductor in Figure 6.

Now referring to Figures 10, 11 and 13, Figure 10 illustrating one of the positions assumed by the rotor just as the inductors are about to break away from the pole pieces to generate a maximum current in the coil. The inductor 9 is just about to break away from the pole piece 5 while the inductor 12 is just about to break away from the pole piece 3. Just prior to the break, the flux path has been from the magnet pole piece

3 thru the inductor 12, the core pole piece 6, the core of the coil which is bridged across the core pole pieces 5 and 6, the core pole piece 5, inductor 9, magnet pole piece 2 thru the magnet seated on the magnet core 70 pieces 2 and 3, and back to the magnet pole piece 3. At the instant of break, this flux path is ruptured and a peak current is induced in the induction coil, the peak being designated at 18, Figure 13. The cut away 75 portion 15 prevents by-passing of the flux from the magnet pole pieces 3 thru inductor 10, core pole piece 5 and inductor 9 to magnet pole piece 2. After a little less than a quarter revolution, the inductor 10 breaks 80 away from the magnet pole 3 giving the peak 19 and very soon thereafter the inductor 12 breaks away from the core pole piece 6 giving the peak 20. After a little less than a quarter revolution later both inductors 10 and 11 break away from the pole pieces 5 and 3 as is illustrated in Figure 11 giving the peak 21. Substantially a quarter revolution later the inductor 11 breaks away 85 from the core pole piece 6 giving the peak 22, and very soon thereafter the inductor 9 breaks from the magnet pole piece 3 giving the peak 23, and finally substantially 90° later both inductors 9 and 12 again break 90 from the members 5 and 3 giving peak 24, thus completing the cycle. The peaks 19 and 20, 22 and 23 may be discarded for ignition purposes in the running of the magneto by maintaining the contacts 25 of the breaker closed. The cam 26 of the breaker 100 for this purpose is rounded at 27 and 28, and is provided with two cam surfaces 29 and 30 to open the circuit only at the peaks 18 and 21.

It will be noted that the interval between the peaks 18 and 21 is shorter than that between 105 21 and 24, and these intervals may be made relatively longer or shorter as desired, by merely tilting the inductors of a pair toward each other as they are cast in the moulded material of the rotor, and without altering the base structure, carrying the several pole pieces.

In the oscillogram of Figure 12, taken 115 with the rotor illustrated in Figure 4, substantially the same cycle takes place. In this case, however, the two peaks 18' and 21' are not of the same height. In effecting the peak current at 18' the inductors 9 and 12 break simultaneously from the pole pieces 3 and 6, and there is an instantaneous reversal 120 of flux through the coil due to the inductor 10 bridging the pole pieces 3 and 2 while the inductor 12 bridges the pole pieces 6 and 2. With the break at 21' the reversal of the flux through the coil does not take place 125 instantaneously due to the fact that the inductor 9 does not bridge the pole pieces 3 and 5, as shown by the dotted line on the inductor 9 in Figure 11. This bridging does 130

take place just a trifle later and causes an auxiliary peak value 31 of lower value than the peak 21'. In normal running of the engine, however, the lower value of the peak 5 value 21' as compared to the peak value 18' has no appreciable effect and the magneto will function properly even with this difference in intensity of the sparks, thus enabling the use of inductor elements all of 10 the same size and shape, and the late peak 31 has no effect on the already exploded charge within the cylinder.

Having thus described my invention, what I claim is:

15 1. In an ignition apparatus adapted to deliver ignition sparks for firing an internal combustion engine at unequal angular intervals of engine crank shaft rotation, a magneto comprising diametrically spaced magnet pole pieces, and aligned spaced core pole pieces arranged on a cylindrical surface and a cylindrical rotor having pairs of inductors provided with flux breaking points co-operating with the pole pieces, the inductors being so positioned on the rotor that the angular distance between breaking points corresponds to the unequal angular firing intervals desired.

20 2. In an ignition apparatus adapted to deliver ignition sparks for firing an internal combustion engine at unequal angular intervals of engine crank shaft rotation, a magneto comprising diametrically spaced magnet pole pieces, and aligned spaced core pole pieces arranged on a cylindrical surface, and a cylindrical rotor having pairs of inductors provided with flux breaking points co-operating with the pole pieces, the inductors being so positioned on the rotor that the angular distance between breaking points corresponds to the unequal angular firing intervals desired.

25 3. In an ignition apparatus adapted to deliver ignition sparks for firing an internal combustion engine at unequal angular intervals of engine crank shaft rotation, a magneto comprising diametrically spaced magnet pole pieces, and aligned spaced core pole pieces arranged on a cylindrical surface, and all being of equal angular extent, and a cylindrical rotor having pairs of inductors provided with flux breaking points co-operating with the pole pieces, the inductors being so positioned on the rotor that the angular distance between breaking points corresponds to the unequal angular firing intervals desired.

40 4. In an ignition apparatus adapted to deliver ignition sparks for firing an internal combustion engine at unequal angular intervals of engine crank shaft rotation, a magneto comprising diametrically spaced magnet pole pieces, and aligned spaced core pole pieces arranged on a cylindrical surface, said core pole pieces being placed in a plane substantially at right angles to the diameter joining the central points of the faces of the magnet pole pieces, and substantially midway between them, and a cylindrical rotor having pairs of inductors provided with flux breaking points co-operating with the pole pieces, the inductors being so positioned on the rotor that the angular distance between breaking points corresponds to the unequal angular firing intervals desired.

45 5. In an ignition apparatus adapted to deliver ignition sparks for firing an internal combustion engine at unequal angular intervals of engine crank shaft rotation, a magneto comprising diametrically spaced magnet pole pieces, and aligned spaced core pole pieces arranged on a cylindrical surface, and a cylindrical rotor having pairs of inductors provided with flux breaking points co-operating with the pole pieces, the inductors

vals of engine crank shaft rotation, a magneto comprising diametrically spaced magnet pole pieces, and aligned spaced core pole pieces arranged on a cylindrical surface, and all being of equal angular extent, said core pole pieces being placed in a plane substantially at right angles to the diameter joining the central points of the faces of the magnet pole pieces, and substantially midway between them, and a cylindrical rotor 70 having pairs of inductors provided with flux breaking points co-operating with the pole pieces, the inductors being so positioned on the rotor that the angular distance between breaking points corresponds to the unequal 75 angular firing intervals desired.

5. In an ignition apparatus adapted to deliver ignition sparks for firing an internal combustion engine at unequal angular intervals of engine crank shaft rotation, a magneto comprising diametrically spaced magnet pole pieces, and aligned spaced core pole pieces arranged on a cylindrical surface, and a cylindrical rotor having pairs of inductors provided with flux breaking points co-operating with the pole pieces, the inductors being so positioned on the rotor that the angular distance between breaking points corresponds to the unequal angular firing intervals desired.

80 6. In an ignition apparatus adapted to deliver ignition sparks for firing an internal combustion engine at unequal angular intervals of engine crank shaft rotation, a magneto comprising diametrically spaced magnet pole pieces, and aligned spaced core pole pieces arranged on a cylindrical surface, and a cylindrical rotor having pairs of inductors provided with flux breaking points co-operating with the pole pieces, the inductors being so positioned on the rotor that the angular distance between breaking points corresponds to the unequal angular firing intervals desired.

85 7. In an ignition apparatus adapted to deliver ignition sparks for firing an internal combustion engine at unequal angular intervals of engine crank shaft rotation, a magneto comprising diametrically spaced magnet pole pieces, and aligned spaced core pole pieces arranged on a cylindrical surface, and a cylindrical rotor having pairs of inductors provided with flux breaking points co-operating with the pole pieces, the inductors being so positioned on the rotor that the angular distance between breaking points corresponds to the unequal angular firing intervals desired.

90 8. In an ignition apparatus adapted to deliver ignition sparks for firing an internal combustion engine at unequal angular intervals of engine crank shaft rotation, a magneto comprising diametrically spaced magnet pole pieces, and aligned spaced core pole pieces arranged on a cylindrical surface, and all being of equal angular extent, and a cylindrical rotor having pairs of inductors provided with flux breaking points co-operating with the pole pieces, the inductors being so positioned on the rotor that the angular distance between breaking points corresponds to the unequal angular firing intervals desired, and the sum of the arcuate distances between the opposite ends of the inductors of one pair being equal to the arcuate distance from the breaking edge of the magnet pole piece to the corresponding edge of the core pole piece.

95 9. In an ignition apparatus adapted to deliver ignition sparks for firing an internal combustion engine at unequal angular intervals of engine crank shaft rotation, a magneto comprising diametrically spaced magnet pole pieces, and aligned spaced core pole pieces arranged on a cylindrical surface, and all being of equal angular extent, and a cylindrical rotor having pairs of inductors provided with flux breaking points co-operating with the pole pieces, the inductors being so positioned on the rotor that the angular distance between breaking points corresponds to the unequal angular firing intervals desired, and the sum of the arcuate distances between the opposite ends of the inductors of one pair being equal to the arcuate distance from the breaking edge of the magnet pole piece to the corresponding edge of the core pole piece.

100 10. In an ignition apparatus adapted to deliver ignition sparks for firing an internal combustion engine at unequal angular intervals of engine crank shaft rotation, a magneto comprising diametrically spaced magnet pole pieces, and aligned spaced core pole pieces arranged on a cylindrical surface, and a cylindrical rotor having pairs of inductors provided with flux breaking points co-operating with the pole pieces, the inductors

- being so positioned on the rotor that the angular distance between breaking points corresponds to the unequal angular firing intervals desired, at least one pair of said inductors being symmetrical with respect to a given plane through the axis of rotation.
8. In an ignition apparatus adapted to deliver ignition sparks for firing an internal combustion engine at unequal angular intervals of engine crank shaft rotation, a magneto comprising diametrically spaced magnet pole pieces, and aligned spaced core pole pieces arranged on a cylindrical surface, and all being of equal angular extent, said core pole pieces being placed in a plane substantially at right angles to the diameter joining the central points of the faces of the magnet pole pieces, and substantially midway between them, and a cylindrical rotor having pairs of inductors provided with flux breaking points co-operating with the pole pieces, the inductors being so positioned on the rotor that the angular distance between breaking points corresponds to the unequal angular firing intervals desired, at least one pair of said inductors being symmetrical with respect to a given plane through the axis of rotation and the sum of the arcuate distances between the opposite ends of the inductors of one pair being equal to the arcuate distance from the breaking edge of the magnet pole piece to the corresponding edge of the core pole piece.
9. In an ignition apparatus adapted to deliver ignition sparks for firing an internal combustion engine at unequal angular intervals of engine crank shaft rotation, a magneto comprising magnet and core pole pieces, and a rotor operatively associated with said pole pieces comprising inductors each of the same size and shape arranged in pairs, the inductors of a pair being inclined to one another and being symmetrically arranged with respect to a diametrical axis, the axes of symmetry of the two pairs being inclined to one another.
10. In an ignition apparatus adapted to deliver ignition sparks for firing an internal combustion engine at unequal angular intervals of engine crank shaft rotation, a magneto comprising magnet and core pole pieces arranged, one set with respect to the other on a cylindrical surface and substantially 90° apart and a cylindrical rotor operatively associated with said pole pieces having inductors inclined to one another.
11. In an ignition apparatus adapted to deliver ignition sparks for firing an internal combustion engine at unequal angular intervals of engine crank shaft rotation, a magneto comprising magnet and core pole pieces arranged, one set with respect to the other on a cylindrical surface and substantially 90° apart and a cylindrical rotor operatively associated with said pole pieces having inductors each of the same size and shape arranged in pairs, the inductors of a pair being inclined to one another and being symmetrically arranged with respect to a diametrical axis, the axes of symmetry of the two pairs being inclined to one another.
12. In an ignition apparatus adapted to deliver ignition sparks, a magneto having means for creating a magneto-motive force in a path comprising fixed pole pieces and stationary core pole pieces, and a core associated with said core pole pieces; a coil wound about said core, means for passing the flux from said magnet pole pieces thru said core and coil alternately in opposite directions consisting of symmetrical rotatable inductors symmetrically arranged with respect to a given plane through the axis of rotation and adapted to complete the flux path at unequal angles of angular rotation thereof.
13. A magneto for generating ignition sparks at alternately longer and shorter intervals, comprising a magnet field structure having uniform parallel pole pieces, and a coil structure having pole pieces arranged in tandem and parallel to said first mentioned pole pieces, and a rotor having inductors for directing the magnetic flux through said coil structure, said inductors being symmetrical and inclined to one another at an angle corresponding to the firing intervals desired.

In testimony whereof, I affix my signature
EDWARD B. NOWOSIELSKI.
